C. P. CASS

AUTOMATIC DRAIN VALVE

Filed Sept. 27, 1923

INVENTOR
CHRISTOPHER P. CASS
BY *Wm. M. Cady*
ATTORNEY

UNITED STATES PATENT OFFICE.

CHRISTOPHER P. CASS, OF BERKELEY, CALIFORNIA, ASSIGNOR TO THE WESTINGHOUSE AIR BRAKE COMPANY, OF WILMERDING, PENNSYLVANIA, A CORPORATION OF PENNSYLVANIA.

AUTOMATIC DRAIN VALVE.

Application filed September 27, 1923. Serial No. 665,112.

To all whom it may concern:

Be it known that I, CHRISTOPHER P. CASS, a citizen of the United States, residing at Berkeley, in the county of Alameda and

5 State of California, have invented new and useful Improvements in Automatic Drain Valves, of which the following is a specification.

This invention relates to drain valves for 10 automatically draining fluid pressure storage reservoirs of liquid which accumulates therein.

The principal object of my invention is 15 to provide an improved automatic drain valve of the above character.

In the accompanying drawing, the single figure is a diagrammatic view, illustrating my improved drain valve applied to a storage reservoir.

20 According to my invention, the drain valve is designed to be employed in connection with a fluid pressure brake system and is adapted to open when fluid is supplied to the brake cylinder to apply the brakes.

25 As shown in the drawing, the drain valve may comprise a casing 1 having a valve chamber 2 connected by pipe 3 with a reservoir 4 in which fluid under pressure is stored. The valve chamber 2 contains a

30 valve 5 for controlling communication from pipe 3 to a drain outlet 6 and said valve is provided with an operating stem 7 which is mounted in a bore of the piston stem 8 of a piston 9.

35 In chamber 10 at one side of piston 9 is a coil spring 11 acting on piston 9 and said chamber is connected by pipe 12 to a timing reservoir 13.

The usual brake cylinder 14 is connected 40 to chamber 15 at the opposite side of piston 9 and said piston is provided with an equalizing port 16.

45 In operation, when the brakes are not applied, the chamber 15 will be at atmospheric pressure and spring 11 will maintain piston 9 in its outer position as shown in the drawing, permitting spring 17 to maintain the drain valve 5 seated.

50 When the brakes are applied, fluid under pressure will also be supplied from the brake cylinder 14 to chamber 15 and piston 9 will thereupon be moved to the right, so

that the valve 5 will be lifted from its seat, permitting any liquid which may have accumulated in the reservoir 4 to drain out 55 past the open valve 5 to the drain outlet 6.

When the fluid pressures have substantially equalized on opposite sides of piston 9 by flow through the restricted port 16, the time being dependent upon the size of the 60 timing reservoir 13 and the size of the port 16, the spring 11 will be effective to shift the piston 9 to the left, permitting the drain valve 5 to close. When the brakes are released, fluid under pressure in chamber 15 65 is also released, as well as fluid in the timing reservoir 13 and chamber 10 by way of the restricted port 16.

In order to prevent possible leakage from the brake cylinder past the stem 7 when the 70 brakes are applied, the end of the stem 9 may be arranged to seat on a gasket 18 when the piston 9 is shifted to its right hand position.

The above described construction utilizes 75 the fluid pressure employed to apply the brakes for opening the drain valve, but the drain valve is prevented from remaining open throughout the brake application which would tend to waste fluid under 80 pressure in the storage reservoir by escape past the drain valve, since the operation of the timing feature causes the drain valve to be closed after a predetermined time period which can be made of short duration, 85 just sufficient to permit the desired draining of the reservoir.

Having now described my invention, what I claim as new and desire to secure by Letters Patent, is:—

1. The combination with a reservoir, of a valve for draining said reservoir, a brake cylinder, means operated by fluid under pressure supplied to the brake cylinder for opening said valve, and a timing reservoir, 95 an increase in pressure in which tends to operate said means to permit said valve to close.

2. The combination with a reservoir, of a valve for draining said reservoir, a brake cylinder, a piston operated by fluid supplied to the brake cylinder for opening said valve, means for equalizing the fluid pressures on opposite sides of said piston, and a spring 100

tending to move said piston to a position permitting the drain valve to close.

3. The combination with a reservoir, of a valve for draining said reservoir, a piston for operating said valve, a brake cylinder connected to one side of said piston, and a timing reservoir connected to the opposite

side of said piston, said piston having a restricted equalizing port for establishing communication from one side to the other side of the piston. ¹⁰

In testimony whereof I have hereunto set my hand.

CHRISTOPHER P. CASS.
